UNITED STATES PATENT OFFICE.

ANGELICA WAEILTY, OF SOUTH SAN FRANCISCO, CALIFORNIA.

CLAMP.

1,342,362.

Specification of Letters Patent.

Patented June 1, 1920.

Application filed January 25, 1919. Serial No. 273,066.

To all whom it may concern:

Be it known that I, ANGELICA WAEILTY, a citizen of the United States, residing at South San Francisco, in the county of San Mateo and State of California, have invented new and useful Improvements in Clamps, of which the following is a specification.

This invention relates to devices for securing cover cloths upon ironing boards and aims to provide a device of this character which is simple of construction and use and which may be readily secured in position upon the board.

15 To this end the invention comprises a clamp positioned longitudinally along the underside of an ironing board and provided with means for holding the edges of the cover cloth after the latter has been 20 stretched over the upper side of the board.

25 The invention also consists of novel means for attaching the edges of a cover cloth to the clamp and for holding the said edges in position, this means providing for the ready removal and replacing of the cover cloth when desired.

30 The invention further includes the following novel details of construction, combination and arrangement of parts to be herein- 35 after more fully described and illustrated in the accompanying drawings.

In the drawings:—

Figure 1 is a side elevation showing the invention applied to an ironing board; 35 Fig. 2 is a bottom plan view of the ironing board;

Fig. 3 is a perspective view of the clamp removed from the board;

Fig. 4 is a fragmentary plan view of the 40 base bar of the clamp; and

Fig. 5 is a detail sectional view on the line 5—5 of Fig. 4.

Referring in detail to the drawings, wherein like characters of reference denote 45 corresponding parts, the ironing board is indicated at 10 and may be of any desired form or construction, either of the type which carries its own supports, or a board independent of its supporting means.

50 The invention resides in the manner of securing a cover cloth 11 to the board and comprises a clamp 12, which includes a base bar 13 and a cover bar 14.

The base bar 13 is formed from a strip 55 of metal having a reduced right angular ex-

tension at one end thereof to provide a combined spacing and hinge bar 15, the hinge being formed by bending over the end of the extension 15 for the reception of the hinge pin.

60 The cover bar 14 is also formed from a strip of metal, one end of which is bifurcated and rolled as shown at 16, so that the hinge pin 17 may be passed through these roller ends and through the end of the end 65 of the extension 15. By this means the bar 14 is hinged to the bar 13, with the two bars spaced apart. The opposite end of the bar 14 is longitudinally slotted as shown at 18 for the reception of a fastening device in 70 the form of a pivoted link 19 secured to one end of the bar 13. This link is adapted to enter the slot 18 and is provided with a cross bar 20 which is pivotally secured thereto so as to be turned transversely across the 75 slot 18 of the bar 14.

75 Projecting at right angles from the bar 13, is a row of spaced pointed elements 21, in the form of pins struck up from the bar 13. These pins are of sufficient length to 80 slightly contact with the adjacent face of the bar 14 and bridge the intervening spaces between the two bars.

85 The clamp is secured to the under face of the ironing board 10 through the medium of screws 22, which pass through openings 23 provided in the bar 13 and when used one edge of the cover cloth is engaged over the pointed elements 21 and then stretched around the board and the other edge engaged. The cover bar 14 is then secured in 90 position through the medium of a pivoted bar 20.

95 The device as shown and described comprises an exceedingly simple means for accomplishing the purpose intended, being cheap to manufacture and easily secured to the board. It is susceptible of various changes in its form, proportions and minor details of construction and the right is reserved to make such changes as will properly fall within the scope of the appended 100 claims.

Having described the invention, what is 105 claimed is:—

1. The combination with an ironing board, of a base bar secured along the longitudinal center and upon the under side of the board, a cover bar hingedly secured to and spaced from one end of the base bar, fastening 110

means located at the other end of the bars and pointed elements struck up from the base bar and contacting with the cover bar.

2. A device of the class described comprising a base bar stamped from a single sheet of metal, pointed elements disposed longitudinally along the center of the said bar and formed by providing spaced pairs of divergently arranged slits and by bend-

ing the material between said slits at right angles to the bar and a right angular extension provided upon one end of the bar, a cover bar hingedly secured to the end of the said extension and means located at one end of the bars for securing them in substantially parallel relation. 15

In testimony whereof I affix my signature.
ANGELICA WAELEY.
